UNITED STATES PATENT OFFICE.

PERRY D. INHOFE, OF DES MOINES, IOWA, ASSIGNOR TO C. B. HESS, OF DES MOINES, IOWA.

VAPORIZER FOR INTERNAL-COMBUSTION ENGINES.

Application filed July 6, 1925. Serial No. 41,472.

The object of my invention is to provide a vaporizer for internal combustion engines of simple, durable and comparatively inexpensive construction.

More particularly, my invention relates to an attachment wherein a supply of water may be fed into a heating chamber, a small amount at a time wherein the steam created in the heating chamber may then be drawn into the intake manifold of the engine.

Still a further object is to so mount the heating chamber relative to the reservoir that only a drop or two of water is permitted to flow from the reservoir to the heating chamber at a time.

With these and other objects in view, my invention consists in the construction, arrangement and combination of the various parts of my device, whereby the objects contemplated are attained, as hereinafter more fully set forth, pointed out in my claim, and illustrated in the accompanying drawings, in which

Figure 1 is a side view of an internal combustion engine with my improved vaporizer device installed therein.

Figure 2 is a top, plan view of my vaporizer device.

Figure 3 is a vertical, sectional view taken on line 3—3 of Figure 1; and

Figure 4 is a detail, sectional view taken on line 4—4 of Figure 2.

In the accompanying drawings, I have used the reference numeral 10 to indicate generally an internal combustion engine, which includes an engine block 11, the exhaust manifold 12 and an intake manifold 13.

The engine block 11 has mounted therein a number of engine bolts 14.

My improved vaporizer device includes a reservoir or tank 15 mounted upon a supporting bracket 16 which has a plurality of openings 17 therein. The engine bolts 14 extend through the openings 17 and anchor the reservoir 15 on to the engine block 11, as clearly shown in Figure 1 of the drawings.

A supporting brace 18 is fastened to the reservoir 15 and is connected to a bolt 19, which is mounted in the engine block 11.

The reservoir 15 has a screw threaded neck 20, which serves as an opening through which water may be placed in the reservoir 15.

A screw threaded cap 21 coats with the neck 20 for serving as a closure member for the reservoir.

A washer 22 is interposed between the cap 21 and the neck 20, as clearly shown in Figure 4 of the drawings, wherein there is provided an air tight sealing joint between the cap and the neck 20.

A heating chamber 23 rests upon the exhaust manifold 12 and has a portion of its bottom curved, as at 24, so as to conform to the contour of the exhaust manifold.

The heating chamber 24 has a pair of brackets 25 extending on one side thereof, which have openings 26.

The engine bolts 14 extend through the openings 26 and serve to retain the heating chamber in position on the exhaust manifold 12.

The heating chamber 23 includes a cover plate 27 which is secured to the main body portion of the chamber 23.

A flexible tube 28 is connected to an extension 29 on the chamber 23 and also to the reservoir 15.

A valve or closure member 30 is positioned adjacent the reservoir 15 wherein the supply of water may be shut off from the chamber 23. The chamber 23 is positioned below the bottom of the reservoir so that water from the reservoir 15 will pass into the chamber 23 by gravity, as will hereinafter be more fully set forth.

Secured to the cover plate 27 is a fitting 31 which has a closing valve 32 therein.

A pipe 33 connects the fitting 31 and is tapped into the intake manifold 13, as clearly shown in Figure 1 of the drawings.

An air inlet opening 34 is formed in the cover plate 27.

The reservoir 15 is designed to be air tight so that when the level of the water within the chamber 23 reaches the point indicated by the reference numeral 35, then no additional amount of water will flow into the chamber 23 because a seal will be formed.

The water within the chamber 23 will become heated and the steam therefrom will be drawn into the intake manifold 13, and as the steam is created, the water within the chamber 23 will be used up and a small amount of additional water will pass then from the reservoir into the chamber 23 because the water level in the chamber 23 will get below the point 35, thereby admitting

air to the tube 28 in the form of bubbles 36 which, due to their buoyancy travel upwardly and into the reservoir 15 thereby displacing a small amount of water which flows downwardly through the tube 28 by gravity and into the vaporizing chamber 23.

It will be seen that I have a gravity feed for permitting the water to pass from the reservoir into the chamber and yet the amount of water passing into the chamber at one time is very small so that the heat of the water within the chamber will be maintained at a boiling point at practically all times.

15 When it is desired not to have any moisture enter through the intake manifold then all that is necessary is to turn the valve member 32 to closed position.

Some changes may be made in the construction and arrangement of the various parts of my invention, without departing

from the real spirit and purpose of my invention, and it is my intention to cover by my claim, any modified forms of structure or use of mechanical equivalents, which may be reasonably included within its scope.

25 I claim as my invention:

A vaporizer including an airtight reservoir adapted to be filled with water, a heating chamber positioned below the reservoir and adapted to rest upon an exhaust manifold of an engine, said heating chamber having a small opening in its top for admitting air, a means of communication between the heating chamber and the reservoir, said means entering the chamber near its bottom whereby the water will be maintained at a predetermined level, and a passage way for drawing steam from the heating chamber into an intake manifold of an engine.

30 35 Des Moines, Iowa, June 26, 1925.
